UNITED STATES PATENT OFFICE.

JOHN H. CARMICHAEL, OF ROANOKE, VIRGINIA.

DESIGN FOR A BOTTLE.

61,131.

Specification for Design.

Patented June 27, 1922.

Application filed March 11, 1921. Serial No. 451,590. Term of patent 3½ years.

To all whom it may concern:

Be it known that I, JOHN H. CARMICHAEL, a citizen of the United States, and a resident of Roanoke, in the county of Roanoke and State of Virginia, have invented a new, original, and ornamental Design for Bottles, of which the following is a specification, reference being had to the accompanying drawings forming part thereof.

Figure 1 is a side elevation, and

Figure 2 is a top plan view of my design for bottles.

I claim:

The ornamental design for a bottle, as shown.

JOHN H. CARMICHAEL.
